UNITED STATES PATENT OFFICE

141,124

DESIGN FOR A PHONOGRAPH NEEDLE

Russell G. Sceli, Canton, Conn.

Application March 16, 1945, Serial No. 118,515

Term of patent 14 years

(Cl. D26—14)

To all whom it may concern:

Be it known that I, Russell G. Sceli, a citizen of the United States, residing at Canton, in the county of Hartford and State of Connecticut, have invented a new, original, and ornamental Design for a Phonograph Needle, of which the following is a specification, reference being had to the accompanying drawing, forming part thereof.

Fig. 1 is a top plan view of a phonograph needle showing my new design.

Fig. 2 is a side elevational view thereof.

I claim:

The ornamental design for a phonograph needle, substantially as shown.

RUSSELL G. SCELI.
